ION SOURCE

Karl Weimer, Gottingen, Germany, assignor to Licentia-Patent-Verwaltungs G. m. b. H., Hamburg, Germany

Application January 6, 1956, Serial No. 557,778

Claims priority, application Germany January 7, 1955

12 Claims. (Cl. 313—63)

This invention relates to an ion source. It relates more particularly to a novel type of an ion source for ionizing gaseous particles.

It is already known in the art to ionize gaseous particles by means of electrons, for instance, those generated by the high frequency field of a high frequency coil or emitted from a cathode.

In order to achieve a pressure difference between the ionization chamber of the ion source and a space provided for accelerating the ions, the hitherto known sources require a narrow channel between the ionization chamber and the above mentioned space, which channel reduces the yield of the ionic source by restricting the beam of the ionic particles.

It is an object of my invention to provide a new ion source with a high yield.

This object is achieved in the ion source according to my invention which source is characterized by the ionization of a stream of gaseous particles travelling in an evacuated chamber with a high and preferably supersonic velocity.

According to a further feature of my invention I provide, in an ion source, a Laval nozzle capable of producing a jet of gaseous particles of supersonic speed.

According to yet another feature of the invention I provide for an adjustment of a gaseous stream in an ion source in such a manner as to cause the development of standing shock waves in said gaseous beam. Thereby I attain the formation of wave nodes in the gaseous beam which fact permits an effective ionization of the gaseous particles in the nodes of the standing shock waves.

The high density of gaseous particles in the supersonic jet and, in particular, due to the formation of a standing shock wave, in the nodes of the latter, facilitates ionization of the particles, and consequently leads to a higher yield of ionized particles than can be attained with the known devices.

In a preferred embodiment of the invention as herein-after more fully described, the ion source comprises an evacuated chamber to which pumping means are connected. A stream of gaseous particles is introduced into this evacuated chamber as a supersonic jet. In the chamber, the gaseous particles are ionized preferably in a node of a standing shock wave formed by the supersonic jet and separated from the remaining unionized gaseous stream.

The ionized particles are guided to outlet means, which may, for instance, be connected to known means for the separation of isotopes.

It is preferred to provide magnetic fields to separate the ionized particles from the gaseous beam.

In a further preferred embodiment, electric fields are provided for separating the ionized particles from the gaseous beam.

In a particularly advantageous embodiment of the invention, the stream of gaseous particles is introduced with supersonic velocity into the chamber of the ion source and directed on to an opening for pumping means, so that a high vacuum is maintained in the chamber and the gaseous beam is concentrated to occupy only a small part of the chamber.

The injection of gaseous particles at supersonic speed into a chamber, for instance through a Laval nozzle,

2

limits the width of the gaseous particle jet, since the velocity component of the particles in the direction of the jet is greater than the component transverse to said jet, which latter component depends on the diffusion velocity of the gaseous particles over the entire volume of the chamber.

In the known devices, in which gas is caused to flow into an ionization chamber by means of a smaller pressure difference corresponding to a particle velocity below the speed of sound, the pressure prevailing in the chamber is practically uniform.

The supersonic injection of gaseous particles according to the invention offers the important advantage that the conventionally required special means for the restriction of particle flow in the ionization chamber and/or a subsequent acceleration of the ionized particles in the isotope separator can be dispensed with.

The ion source according to my invention permits to attain a much higher yield of ionized particles than the known ion sources, and, nevertheless, practically eliminates the undesirable penetration of unionized particles into that part of the device through which the ionized particles are emitted from the source.

The aforesaid objects and advantages will be better understood at the hand of the detailed description following hereinafter in connection with Figures 1 and 2 of the accompanying drawings wherein Figure 1 is a schematic sectional view of an ion source according to the invention provided with a supersonic jet nozzle and a high frequency coil and other accessories according to the invention.

Figure 2 is another schematic sectional view provided with an electron gun for ionizing the gaseous particles which are introduced into the evacuated chamber with supersonic velocity.

Referring now to the drawings it will be seen that the ion source comprises an evacuated chamber 1 having a supersonic jet nozzle, preferably a Laval nozzle, 2. A stream 3 of gaseous particles enters the evacuated chamber 1 with supersonic velocity through the supersonic jet nozzle 2. The stream 3 of gaseous particles is provided from a stock bottle (not shown), which is connected with supersonic jet nozzle 2 by means of a pipe and a throttle (not shown). According to its high velocity the beam 3 of gaseous particles remains concentrated over a relatively long distance. An opening 4 is provided in the evacuated chamber 1 which opening is located opposite the opening 4 which latter is connected via a pipe 7 to a pump 5. Hollow vessels 18 combined with the wall parts 6 of the chamber 1 and the part 7a of the pipe 7 between the opening 4 and the pump 5 are preferably provided for containing cooling media so that a high vacuum in the chamber 1 is maintained. Between the wall parts 6 and the adjacent wall parts 1a of the chamber 1, on the one hand, between pipe parts 7a and the remaining part of pipe 7 leading to the pump 5, intermediate pieces 12 are arranged for thermic insulation.

As an example in the Figures 1 and 2 an adjustment of the gaseous beam is shown which leads to the formation of shock waves resembling a standing wave.

In order to obtain a high rate of ionization the ionizing means are arranged in the neighborhood of a node 8 of particle stream 3. For instance in Figure 1 a high frequency coil 9, and in Figure 2 an electron beam 15, are provided for ionization. The electron beam 15 is generated by an electron source 16 and directed through a node 8 on to a target 17 which latter is at a desired potential.

The beam 13 of ionized particles is separated from the beam 3 of gaseous particles by means of a magnetic field and preferably guided by the same field through

an opening 10 into an accelerating tube 11. The tube 11 may be connected to conventional means 22 for the separation of isotopes. In Figures 1 and 2, the dotted line indicates the poles 20 and 21, respectively, of a magnet (not shown).

By using an ion source according to the invention, it is possible to provide a relatively large opening 10. Consequently, the yield of the ion source is not restricted by too narrow an opening 10. This advantage can preferably be achieved by ionizing gaseous particles in a concentrated gaseous beam in such a manner that already in those parts of the chamber 1 adjacent to the opening 10, a relatively high vacuum is maintained.

It will be understood that this invention is susceptible to modification in order to adapt it to different usages and conditions, and, accordingly, it is desired to comprehend such modifications within this invention as may fall within the scope of the appended claims.

I claim:

1. In an ion source comprising an evacuated chamber, pumping means connected with said evacuated chamber, means for introducing a stream of gaseous particles in said evacuated chamber at supersonic speed, means for ionizing a portion of said gaseous particles, means for separating the ionized portion of said particles from said stream of gaseous particles, and outlet means for said ionized particles.

2. In an ion source comprising an evacuated chamber, pumping means connected with said evacuated chamber, jet producing means for introducing a stream of gaseous particles in said evacuated chamber, which stream leaves said jet producing means with supersonic velocity and develops a standing shock wave in said chamber, means for ionizing a portion of said particles, means for separating the ionized particles from said stream of gaseous particles, and outlet means for said ionized particles.

3. In an ion source comprising an evacuated chamber, jet producing means for introducing a stream of gaseous particles in said evacuated chamber, which stream leaves jet with supersonic velocity, means for ionizing a portion of said particles, means for separating the ionized particles from said stream of gaseous particles, pumping means for removing said gaseous particles from said evacuated chamber, said evacuated chamber having an opening opposite said jet producing means, to which opening said pumping means are connected, whereby said stream of gaseous particles is directed toward said opening, and outlet means for said ionized particles.

4. In an ion source comprising an evacuated chamber, jet producing means for introducing a stream of gaseous particles in said evacuated chamber, said stream leaving said jet producing means with supersonic velocity, means for ionizing a portion of said particles, means for separating the ionized particles from said stream of gaseous particles, pumping means for removing the remaining gaseous particles from said evacuated chamber, the opening for said pumping means being arranged opposite to said jet producing means, cooling means arranged adjacent to said opening for said pumping means, and outlet means for said ionized particles, disposed at an angle to said stream of gaseous particles.

5. In an ion source comprising an evacuated chamber, pumping means connected with said evacuated chamber, means for introducing a stream of gaseous particles with supersonic velocity into said evacuated chamber so as to form a standing shock wave therein, means for ionizing a portion of said particles, said ionizing means being arranged so that the ionization of said gaseous particles takes place in at least one node of said standing shock wave of gaseous particles, means for separating the ionized particles from said stream of gaseous particles, and outlet means for said ionized particles.

6. In an ion source comprising an evacuated chamber, pumping means connected with said evacuated chamber, means for introducing a stream of gaseous particles with

supersonic velocity in said evacuated chamber, high frequency means for ionizing a portion of said particles, means for separating the ionized particles from said stream of gaseous particles, and outlet means for said ionized particles.

7. In an ion source comprising an evacuated chamber, pumping means connected with said evacuated chamber, means for introducing a stream of gaseous particles with supersonic velocity in said evacuated chamber, high frequency coil means, said gaseous particles traversing said high frequency coil means and a portion of said particles being ionized by the high frequency field of said high frequency coil means, means for separating the ionized particles from said stream of gaseous particles, and outlet means for said ionized particles.

8. In an ion source comprising an evacuated chamber, pumping means connected with said evacuated chamber, means for introducing a stream of gaseous particles with supersonic velocity in said evacuated chamber, means for generating and accelerating electrons, said electrons being directed on to said stream of gaseous particles for ionizing a portion of said gaseous particles, means for separating the ionized particles from said stream of gaseous particles, and outlet means for said ionized particles.

20 9. In an ion source comprising an evacuated chamber, pumping means connected with said evacuated chamber, means for introducing a stream of gaseous particles with supersonic velocity in said evacuated chamber, means for ionizing a portion of said particles, electric means for separating the ionized particles from said stream of gaseous particles, and outlet means for said ionized particles.

25 10. In an ion source comprising an evacuated chamber, pumping means connected with said evacuated chamber, means for introducing a stream of gaseous particles with supersonic velocity in said evacuated chamber, means for ionizing a portion of said particles, magnetic means for separating the ionized particles from said stream of gaseous particles, and outlet means for said ionized particles.

30 11. In an ion source comprising an evacuated chamber, pumping means connected with said evacuated chamber, means for introducing a stream of gaseous particles with supersonic velocity in said evacuated chamber, means for ionizing a portion of said particles, means for separating the ionized particles from said stream of gaseous particles, and outlet means for said ionized particles.

35 12. In an ion source comprising an evacuated chamber, pumping means connected with said evacuated chamber, a Laval nozzle for introducing a stream of gaseous particles with supersonic velocity into said evacuated chamber in order to develop a standing shock wave having at least one node therein, said chamber having an opening opposite said Laval jet, pumping means connected with said opening, said stream of gaseous particles being concentrated to occupy only a small part of said chamber and being directed toward said opening, means for ionizing a portion of said particles and comprising a high frequency coil disposed in the region of a node of said shock wave, said coil being adapted to generate a high frequency field which ionizes said gaseous particles in said node, magnetic means for separating the ionized particles from said stream of gaseous particles, and outlet means for said ionized particles, said outlet means being disposed substantially at a right angle to the direction of said stream of gaseous particles from said Laval nozzle to said opening, and permitting an unobstructed flow of said ionized particles from said chamber to the outside thereof.

40 13. In an ion source comprising an evacuated chamber, pumping means connected with said evacuated chamber, means for introducing a stream of gaseous particles with supersonic velocity into said evacuated chamber so as to form a standing shock wave therein, means for ionizing a portion of said particles, said ionizing means being arranged so that the ionization of said gaseous particles takes place in at least one node of said standing shock wave of gaseous particles, means for separating the ionized particles from said stream of gaseous particles, and outlet means for said ionized particles.

45 14. In an ion source comprising an evacuated chamber, pumping means connected with said evacuated chamber, means for introducing a stream of gaseous particles with supersonic velocity into said evacuated chamber so as to form a standing shock wave therein, means for ionizing a portion of said particles, said ionizing means being arranged so that the ionization of said gaseous particles takes place in at least one node of said standing shock wave of gaseous particles, means for separating the ionized particles from said stream of gaseous particles, and outlet means for said ionized particles.
